T. A. MEYERS

PACKING FOR PISTONS

Filed April 15, 1921

Fig. 2.

INVENTOR:
Theodore A. Meyers,
By Monroe Hall, Atty.

UNITED STATES PATENT OFFICE.

THEODORE A. MEYERS, OF TOLEDO, OHIO.

PACKING FOR PISTONS.

Application filed April 15, 1921. Serial No. 461,545.

To all whom it may concern:

Be it known that I, THEODORE A. MEYERS, a citizen of the United States, residing at Toledo, in the county of Lucas and State of Ohio, have invented certain new and useful Improvements in Packings for Pistons; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to new and useful improvements in packing for piston-rods, valve-stems, plungers and similar structures, and is designed to furnish a simple and efficient packing which will not only provide 20 a joint or joints which completely prevents the escape of fluids around or through the packing, but which will accommodate itself to the irregularities of worn or scored surfaces with which it may come in contact.

25 My packing is also designed to provide a degree of resiliency which adapts it for a considerable range of variation in the sizes of the annular chambers in which the packing may be employed, as well as changes due to 30 contraction and expansion.

With these and other objects and advantages in view, my invention consists of the devices, construction and arrangement of parts hereinafter described, and illustrated 35 in the accompanying drawings, in which—

Figure 1, is a central, longitudinal, sectional view of my packing applied to a piston-rod and an ordinary stuffing-box, and Fig. 2, a perspective view of a short section 40 of one of my packing-rings, detached.

My packing is formed preferably in elongated strips which are divided into suitable lengths to encircle, as a ring, the rod to be packed. Viewed in cross-section, my packing 45 may be considered as consisting of two principal parts, namely, the rectangular portion *a* and the portion *b*, which is of the same width as the part *a* and which is preferably arched as shown. The part *b* may, for convenience, be termed the cushion. The part *a* is built up of superposed layers of rubberized fabrics, the layers being closely compressed together. The fabric may consist of any suitable fibrous material, as, for instance, cotton duck, asbestos, flax, hemp, jute 50 or the like, woven or braided, depending

upon the nature of the fluids to be confined, whether water, steam, acids, gases or other fluids, as well as the degree of temperature to which the packing is to be subjected. The 60 part *b* is composed of the same material, wound or fashioned in such manner as to leave a longitudinal central tubular opening *c* therethrough. Throughout the length of this opening is a closely fitting, flexible, heat 65 and oil-resisting tube *d*. This tubing is readily obtainable upon the market, but I am unable here to explain its composition. The office of this tube is to lend resiliency to the cushion part *b* as well as to aid in 70 maintaining the cross-sectional contour of the packing-rings.

The part *a* of the packing is divided diagonally, as at *e*, so that when the packing-rings are under compression, the inner and the outer triangular portion *f*—*g*, will slide upon each other in wedge-like fashion, which will spread them apart in the annular space around the piston and effecting their movement in the direction of the length of 80 the piston. Thus each member or part of the packing-ring contributes to the elastic transverse spreading of the ring, internally and externally, and to the close contact of the rings with the opposed surfaces of the 85 piston and the stuffing-box.

The several parts above described are wrapped and held assembled in operative relation by means of a light fabric, woven or braided, of suitable material, such as cotton 90 yarn or asbestos, depending upon the service for which the packing is designed. The several packing-rings are disposed with the flat sides *h* of the triangular portions *g* turned in the direction of the gland or follower of the stuffing-box, so that, under compression, the cushions of the successive rings 95 will contact with the surfaces *h* of the adjacent rings.

The lubricants to be employed with my 100 packing, such as oils, greases, mica or graphite, or mixtures of the same, are a matter of selection, and will vary under different conditions of temperature, and with the different fluids to be confined, as will be understood by those skilled in the art without explanation in this specification.

Having described my invention, what I claim and desire to secure by Letters Patent of the United States, is—

1. An expandible packing embodying a resilient section provided with a chambered

- rubber core, and parallel therewith a pair of relatively slideable sections coacting for relative shifting in effecting opposite packing.
- 5 2. An expansible packing embodying a resilient section provided with a chambered core, a fabric body section about said core, and relatively shiftable triangular sections movable as to the resilient section.
- 10 3. An expansible packing embodying a resilient section provided with a tubular rubber core, a pair of parallel fabric body triangular sections, and a jacket for assembling said sections as a unit.
4. An expansible packing embodying a 15 resilient section provided with a tubular rubber core, said resilient section having plies of fabric wrapped about said rubber core as a body, and relatively slideable sections having parallel plies of fabric extending 20 into said sections from the opposing faces thereof.

In testimony whereof I affix my signature in presence of two witnesses.

THEODORE A. MEYERS.

Witnesses:

ELMER L. SKIDMORE,
JENNIE FLY.
